UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,256,990.

Specification of Letters Patent. Patented Feb. 19, 1918.

Application filed October 16, 1916. Serial No. 125,891.

To all whom it may concern:

Be it known that I, FRANK DUTCHER, a citizen of the United States, residing at Versailles, in the county of Allegheny and State of Pennsylvania, have invented certain new and useful Improvements in Railway Signal-Torpedoes, of which the following is a specification, reference being had therein to the accompanying drawing.

10 This invention relates to improvements in railway signal torpedoes, and pertains to a paper or fiber case torpedo circular in form with a bulged top, which type is referred to in the trade sometimes as "button-top" and at other times as "bull's-eye" torpedoes.

15 The primary object of my present invention is to provide a paper case torpedo of the foregoing type with a metal ring-like clamp for closing the abutting edges of the several 20 parts of the case in such a tight manner as to make a waterproof joint without the use of cement.

25 A further object of my invention is to provide a metal ring-like clamp closure for the aforesaid type of paper case torpedo, which not only serves to make a water-tight joint without the use of cement, but also leaves the paper bottom of the torpedo exposed so that the cement holding the sand 30 to the bottom is placed on the paper surface instead of a metal surface thereby making it easier to apply and not liable to peel as when applied to metal and therefore more efficient.

35 In the accompanying drawings—

Figure 1 is a perspective view of a torpedo with my improved metal clamp applied thereto.

Fig. 2 is a transverse sectional view of

40 Fig. 1.

Fig. 3 is an enlarged transverse sectional view of the abutting edges of the paper case and metal clamp.

45 Fig. 4 is a perspective view of the several parts going to make up the torpedo, the parts shown in separated relation.

Fig. 5 is a sectional view showing an additional metal clamp for uniting a spring rail-engaging strap to the torpedo.

50 Fig. 6 is a bottom plan view of the construction shown in Fig. 5.

Fig. 7 is a detached broken perspective view of the clamping ring.

Referring now to the drawings, 1 is a

button top or bulged portion of the torpedo 55 which is composed of paper or suitable fiber. Placed within this button top 1, is a suitable molded or plastic explosive 2. This button top 1 is provided with a laterally extending annular flange 3. After the explosive 2 is placed within the top 1, a paper disk 4 is placed outside of the explosive and of a size sufficient to abut or engage the under side of the flange 3, as clearly shown in Figs. 2 and 3. A second rail-strap holding paper disk 5 is placed outside of the disk 4, and is of a size corresponding therewith, and is provided with suitable openings 6, for the reception of a rail engaging strap 7.

These parts 1 to 5, inclusive, assembled as described, are placed in a clamping ring 8, which in its unclamping shape is essentially L-shape in cross-section. With these parts so assembled the upwardly extending 75 flange 9 is clamped down upon the outside of the flange 3, and the lower wall or portion 10 of this clamping ring 8 is under and against the disk 5. This clamping action is performed by suitable dies (not 80 shown) so that the edges 11 and 12 of the walls 9 and 10 are caused to tightly clamp the several engaging portions 3, 4 and 5 of the case. It will be observed from Figs. 3 and 7 that the clamping ring 8 is approximately 85 U-shaped in cross-section with the under leg or wall 10 of the U preferably longer than the upper wall 3.

By reason of this type of clamping ring, I am enabled to force the two walls 10 and 90 3 so tight that they compress and hold the parts 3, 4 and 5, so tight as to make a water-tight joint, and this is facilitated by being able to force inward the edges 11 and 12 of the upper and lower wall.

95 In Figs. 6 and 7, I show a well-known type of metal clip 13 for holding the strap 14 to the torpedo, instead of having it pass through openings in the wall 5, and this is particularly intended for use in connecting 100 a spring strap 14 to the torpedo. The opening out of the spring-rail strap 14 causes a strain on the holding member so great that paper or fiber is not well adapted to withstand the strain, and hence when a spring 105 strap is to be used, the metal clip 13 is preferably provided.

From my experience in the manufacture

of paper torpedoes, the uniting of the parts of the paper case by cement has been found to be commercially successful when all the conditions are exactly right, viz., when the proper kind of cement is used and when it is carefully and properly placed on the parts by the persons assembling and cementing the torpedoes. It has also been found that the character of waterproof cement to be used is such that the dissolving liquid is of a volatile character. Because of this the consistency of the cement is constantly changing and it requires skill and care to keep the cement in the proper condition to afford proper and satisfactory results. Again, the cement must be carefully applied so as to cover properly all of the parts to be cemented together.

It is well-known to those skilled in the art that these torpedoes are manufactured and sold at a price generally less than two cents apiece and, consequently, cheap labor must be employed to do the work and the work must be rapidly done to be able to manufacture and sell the torpedoes at that price and with a profit, to which expense must be added the over-head expense.

The necessity for carefulness in the consistency of the cement and the applying of it to the torpedo, is obviated by the use of a ring-like clamp, such as herein shown and described. These clamps when in the form shown in Fig. 4, are manufactured by machinery rapidly and are always accurate and the clamping rings are applied by suitable dies (not shown) which will always insure the exact and proper amount of pressure to accomplish a water-tight joint and without the exercise of any judgment on the part of the operator. It is an operation which is quickly and accurately performed by a machine in the hands of cheap labor.

I am aware that it is not new to provide a metal clamp for a paper case torpedo, such, for instance, as is shown in the patent to Lafferty, No. 676,327, of June 11th 1901. These torpedoes were for several years manufactured and sold, but great difficulty was encountered in making a tight joint and a "packing" flange was necessary. The practical difficulty found with this type of torpedo was that the parts of the paper case could not be tightly clamped, when as in the prior structures the bottom wall of the clamp extended entirely across the bottom of the paper case. It did not provide the possibility of forcing the edges of the two walls tightly against the adjoining parts of the paper case, therefore a "packing" flange was necessary, as stated in that patent. All of these practical difficulties are overcome by the use of my type of torpedo with the surrounding flange extending beyond the ex-

plosive and the clamping ring approximately U-shaped in cross-section, whereby the upper and lower walls of the clamping ring can be made to tightly clamp the paper parts of the case together and make a water-tight joint, and in a manner always uniform and accurate by the use of machinery for that purpose.

While I prefer to use the second paper disk 5, I desire it to be understood that this is not essential for the successful use of the clamping ring to make a tight and waterproof joint of the abutting members of the paper case. Of course, by omitting the outer paper disk 5, some other means must be provided for holding the rail strap 7, such for instance, as that shown in Figs. 80 5 and 6, although any other of the various ways shown in the art for connecting the rail engaging strap that would be adapted to this structure could be used.

This ring-like clamp leaves the bottom 85 of the paper case of the torpedo exposed, so that the sanded coating 15 can be applied directly to the paper case.

Having thus described my invention, what I claim and desire to secure by Letters Patent is:

1. A fiber railway signal torpedo of the button-top type, comprising a paper case made up of several parts, an explosive compound therein, the peripheries of the several parts having projecting engaging annular flanges, and a ring-like metal clamp approximately U-shaped in cross-section and embracing the said projecting flanges, the parallel parts of the clamping member forcing and compressing the flanges together making a water-tight joint between them and the said clamping member.

2. A fiber railway signal torpedo of the button-top type, comprising a case made up of several parts, an explosive compound therein, the peripheries of the parts of the case provided with annular flanges projecting beyond the explosive, and a ring-like metal clamp approximately U-shaped in cross-section, said member embracing the said flanges and the parallel parts of the clamping member tightly forcing and compressing the adjacent faces of said flanges together and the edges of the parallel portions forcing tightly against and compressing the outer sides of the flanges, whereby a water-tight joint is formed between the flanges and the said clamping member.

In testimony whereof I hereunto affix my signature in the presence of two witnesses.

FRANK DUTCHER.
